UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

990,919.

Specification of Letters Patent. Patented May 2, 1911.

Application filed February 8, 1909. Serial No. 476,653.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to card holders and has for one of its objects to provide a card holder adapted to receive either the top edge of a card or the bottom edge of a card and carry the card with the platen properly to the printing point.

Another object is to provide simple and convenient means for holding the card holder detachably upon the platen.

A further object is to provide a construction whereby the platen with the card holder may be rotated in either direction without being interfered with by the paper feeding or accessory devices.

Still other objects will appear hereinafter.

My invention consists in the various features of construction, combinations and arrangements of devices hereinafter more fully described and particularly pointed out in the appended claims.

In the accompanying drawings:—Figure 1 is a plan view of part of the paper carriage of a Monarch typewriting machine embodying my improvements. Fig. 2 is an enlarged vertical cross-section of the same. Fig. 3 is an enlarged partial front elevation thereof. Fig. 4 is an enlarged longitudinal section of a platen embodying my invention. Fig. 5 is an enlarged end elevation of the same. Fig. 6 is a fragmentary front elevation thereof. Fig. 7 is a fragmentary vertical cross-section of the platen with the card holder in place and showing a card in its grasp.

In the various views the same parts will be found designated by the same numerals of reference.

1 is the top plate of a Monarch machine on which is usually mounted two posts or brackets 2, which support the carriage guide rails 3.

4 is the back bar of the platen frame or carriage which runs on roller bearings 5.

6, 6 are the side bars of the platen frame and in which a cylindrical platen 7 is mounted to rotate as usual in said machine. The ends of the platen shaft are provided

with hand wheels 8, 8 for rotating the platen. The platen is also adapted to be rotated by line spacing mechanism, of which only the line spacing wheel 9 is shown, the hand lever and driving pawl being omitted; the spring detent roller 10 however is illustrated.

11 is a pivoted paper apron or deflector curving around on the under side of the platen, its forward edge being free; 12 the rear pressure rollers; and 13 the front pressure rollers, both of which are shown in dotted lines only.

14 is the platen scale pivotally mounted at 15 at each end upon forwardly extending arms 16. A spring 17, riveted on the arm 16 and bearing on a lug 18 at the lower portion of the platen scale at each end, tends to keep the upper edge of the platen scale against or close to the platen.

19 is a line-finder and pressure device pivotally mounted at 20 upon a bracket 21 and having downwardly extended leg portions 22 whose extremities are turned forwardly as at 23, leaving rounded corners 24. A spring 25 is arranged to keep the upper end of the line-finder and pressure device against the platen with a gentle pressure. This pressure may, however, be increased by an upwardly sliding device 26 which works against the rounded corners 24 to cam them outwardly and thus increase the pressure of the upper end of the device 19 against the platen. This device 19 in the present instance is also provided with an upwardly extending finger portion 27.

All of the devices thus far described or referred to (excepting the finger 27) are in common use on the Monarch typewriter and therefore need no further detail description. The finger 27 is occasionally used for special work.

28 is a card-holder comprising as shown a plate-like device which extends substantially the whole length of the platen. Said card-holder is formed or provided at each longitudinal edge with an under-cut, these edges being marked respectively 29 and 30. Said under-cuts create spaces between the plate and the surface of the platen for the insertion of the edges of cards, the shoulders 31 informed by said under-cuts limiting the introduction of the cards.

The card plate is curved to conform to the curvature of the platen and at its ends is off-set, as at 32, to reach the faces of two

rings 33 and 34, which are secured to the wooden cylinder 35 by screws 36, the rubber sheath or facing 37 of the platen being cut away for the mounting of said rings. The 5 ring 33 is provided with a pin or stud 38 having a flange or button head 39, and the ring 34 is provided with a plain stud or pin 40. These devices serve to position the 10 card-holder properly upon the platen. The card-holder at one end is slotted, as at 41, to embrace the stud 38 under the button head 39 and the other end of the card plate is preferably formed with a perforation 42 to fit upon the pin 40. The forked end of 15 the card plate is first slipped upon the stud 38 and then the perforation is fitted over the pin 40.

For the purpose of securely holding the 20 card plate in position I have provided a locking bail 43, which is pivoted on studs or rivets 44 arranged at diametrically opposite sides of the platen and upon the ring 34. The bail or locking device is generally semi-circular in form but is slightly flattened at its upper middle portion as shown 25 at 45 to bear upon the depressed perforated portion of the card plate and thus clamp or lock the same upon the surface of the platen. The extremity of this depressed end 30 of the card plate is preferably beveled to facilitate the locking operation of the bail when it is swung upwardly and inwardly. When it may be desired to remove the card plate the bail is swung outwardly or in the 35 direction of the arrow at Fig. 6, so as to uncover the depressed portion of the card plate, whereupon the plate is adapted for instant removal. When the card plate is not in use the bail is swung back to the position 40 shown at Fig. 6 and is held there, by the action of the pin 40, the flattened part 45 of the bail having frictional engagement with the top of the pin. The inner edge of the part 45 is preferably beveled to ride 45 up over the pin and over the extremity of the plate more readily, and the bail is light enough to yield and spring in the locking or catching operations.

The card plate is preferably provided 50 near each end with two fins 46 which project forwardly from one of the longitudinal edges of the card plate. The foremost or free ends of these fins are beveled or sharpened to form cams or wedges 47 for 55 the purpose of camming off or lifting the scale plate 14 and the deflector or apron 11 when the platen is rotated backwardly.

The over-hanging lips formed by the under-cuts 29 and 30 are beveled as at 48 and 60 49, the latter more particularly to cam off the pressure rollers, deflector, scale and line-finder when the platen is turned forwardly, that is in the direction to feed the card in regular line space direction. The beveled 65 edge 48 will likewise operate to lift off cer-

tain of the paper feeding devices when the platen is rotated backwardly or in a direction opposite to that of line feeding. The beveled edge 48 is also adapted to cam off the line-finder 19 through the finger portion 70 27, which as shown more particularly in Fig. 2 is bent forward slightly at 27a. The beveled edge 48 enters behind said finger and forces it and the line-finder 19 away from the platen, thus obviating any obstruction to backward rotation of the platen, which might otherwise occur. The fins, being in advance of the card holder proper, successively remove the scale and deflector, so that backward rotation of the platen will 80 not be interfered with by collisions between the card plate and the scale plate or the deflector.

Referring to Fig. 2 it will be observed that the beveled edge 48 of the forward lip of the 85 card plate is about to enter behind the upper end of the finger 27 while the beveled end of the fin 46 is arranged in advance of the beveled edge 48. When the platen is turned in the direction of the arrow the beveled 90 edge 48 will force outwardly the finger 27 and the line-finder 19 so as to make way for the card plate and the beveled fin 46 will later pass behind the scale plate 14 and behind the deflector 11. Both the beveled 95 edges 47 and 48 will also move off the feed rollers 13 and 12. It will also be observed from Fig. 2 that when the platen is rotated in a direction the reverse of that indicated by the arrow the beveled edge 49 of the card 100 holder will cam off the feed rollers 12 and 13, the deflector 11, the scale plate 14 and the line-finder 19.

Referring to Figs. 1 and 7, I have shown a card *a* fitted in working position in the 105 under-cut 29 of the card holder. To feed this card to printing position the platen is turned forwardly or in the direction of the arrow at Fig. 7, or the reverse of the arrow at Fig. 2. The leading edge of the card is 110 brought up to the printing point indicated by the dotted line *a* in Fig. 2. The position at which the writing is to be begun on the card is of course determined by the operator. This printing position may be either 115 close to the edge of the lip or some distance therefrom in accordance with the exigency of the work. The card may be written upon line by line in the usual manner close down to its lowermost edge, this being possible 120 with the line-finder or pressure device 19. If it be desired to write closer to the top edge of the card than may be accomplished with the card-holder arranged as just above explained then the lower edge of the card is 125 inserted in the under-cut 30 and the platen rotated backwardly or in the direction of the arrow shown at Fig. 2 until the top edge of the card is in register with the printing point. Then the card may be fed in the 130

natural, line-space direction as the lines are written. In this case the card may be written upon down as far as that portion which is held by the under-cut.

5. It will thus be seen that I have provided a card holder adapted to enable the card to be printed upon to the extremity of either its top edge or its bottom edge as may be required. It will also be observed that I 10 have provided means on said card holder for moving out of the way any and all devices connected or associated with the paper feed mechanism which might otherwise obstruct the card holder or platen, when the latter is 15 rotated either backwardly or forwardly. While the means just referred to have been provided particularly for the existing construction of Monarch paper feeding devices it will also be understood that if the scale 20 plate be bent slightly forward and the line-finder be similarly bent as well as the paper apron, an uninterrupted passage of the card plate will be permitted without the use of the fins 46 and the finger 27.
25. Various changes may be made without departing from the spirit of my invention, and some of my improvements may be used without others.

What I claim as new and desire to secure 30 by Letters Patent, is:

1. In a typewriting machine, the combination of a platen, a card holder, positioning devices therefor on the platen, and a swinging bail for securing the card holder.
35. 2. In a typewriting machine, the combination of a platen, a card holder, a platen provided with positioning devices at each end, a card holder constructed to engage said positioning devices, and a swinging bail for 40 clamping one end of said card holder.
3. In a typewriting machine, the combination of a platen having at one end a stud with a button head and at its other end a pin, a card holder having at one end a slot or 45 fork to engage said stud under said button head and at the other end having means to engage said pin and a swinging retaining device permanently attached to the platen for clamping the card holder in engagement 50 with said pin.
4. In a typewriting machine, the combination of a platen having at its ends positioning studs or pins, a card holder adapted to engage said studs or pins, and a bail pivoted at diametrically opposite sides of the 55 platen and adapted to be swung over on to one end of the card holder.
5. In a typewriting machine, the combination of a platen having positioning devices 60 thereon, a card holder constructed to engage said positioning devices, and a semi-circular

bail for said card holder pivoted on opposite sides of the platen.

6. In a typewriting machine, the combination of a platen having pins at each end, a card plate under-cut at both edges longitudinally of the platen and off-set at both ends and provided with means to engage said pins, and a swinging bail at one end of the platen to grip one end of said card plate.

7. In a typewriting machine, the combination of a platen, paper feeding devices, a card holder secured upon said platen and provided, on the same side thereof as its card holding portion and in advance of said card holding portion, with camming devices for throwing off the paper feeding devices when the platen is rotated backwardly.

8. In a typewriting machine, the combination of a platen, paper feeding devices, a card holder having an under-cut portion and camming devices arranged on the same side of said card-holder as said under-cut portion and in advance of said under-cut portion.

9. In a typewriting machine, the combination of a platen, a paper scale, a card holder having an under-cut portion, and camming devices arranged in advance of said under-cut portion.

10. In a typewriting machine, the combination of a platen, a platen scale, and a paper deflector, a card holder having an under-cut portion, and camming portions arranged in advance of said under-cut portion.

11. In a typewriting machine, the combination of a platen, a line finder or pressure device having a finger with a bevel or out-turned extremity, and a card holder having a beveled edge.

12. In a typewriting machine, the combination of a platen, paper feed devices co-operating with said platen, and a card holder having under-cut portions at its opposite edges, the over-hanging lips formed by said under-cuts being beveled.

13. In a typewriting machine, the combination of a platen, and a card holder having under-cuts along its opposite edges, beveled lips and beveled fins.

14. A card holder, comprising a plate provided with means enabling it to be detachably attached to a platen and having under-cuts along its opposite longitudinal edges, and having also beveled lips and beveled fins.

Signed at Syracuse, in the county of 115
Onondaga, and State of New York, this 5th
day of February A. D. 1909.

HERBERT H. STEELE.
